BADGE

Arthur J. Merkel, East Cleveland, Ohio, assignor
to Jack & Heintz Precision Industries, Inc.,
Cleveland, Ohio, a corporation of Delaware

Application June 29, 1951, Serial No. 15,708

Term of patent 14 years

(Cl. D29—2)

To all whom it may concern:

Be it known that I, Arthur J. Merkel, a citizen of the United States, residing at East Cleveland, in the county of Cuyahoga and State of Ohio, have invented a new, original, and ornamental Design for Badge, of which the following is a specification, reference being had to the accompanying drawing, forming part hereof, wherein:

Figure 1 is a view in perspective of a badge showing my new design;

Figure 2 is a view in front elevation of the same; and

Figure 3 is a top plan view of the same.

I claim:

The ornamental design for a badge, substantially as shown.

ARTHUR J. MERKEL.
